UNITED STATES PATENT OFFICE.

JOHN N. KAILOR AND MARSHAL T. REEVES, OF COLUMBUS, INDIANA,
ASSIGNORS TO THE REEVES & COMPANY, OF SAME PLACE.

DESIGN FOR A CONCAVE-SECTION FOR SEPARATORS.

SPECIFICATION forming part of Design No. 28,454, dated April 5, 1898.

Application filed January 29, 1898. Serial No. 668,493. Term of patent 14 years.

To all whom it may concern:

Be it known that we, JOHN N. KAILOR and MARSHAL T. REEVES, citizens of the United States, residing at Columbus, in the county 5 of Bartholomew and State of Indiana, have invented and produced a new and original Design for Concave-Sections for Separators, of which the following is a specification.

10 The accompanying drawings illustrate our design for concave-sections for separators.

Figure 1 is a perspective view of one of said sections embodying our design. Fig. 2 is an end elevation thereof.

15 Our concave is arc-shaped in cross-section and is provided on its under side with a series of ribs 4, the outer faces of the two outer

ones being radial to the center of the curve of the upper face 5.

The essential or leading features of our design consist of the two series of grooves 6 and 7, which cross each other at an angle, and thus form a series of pyramids 8 upon the face of the concave and a series of openings 9, which pierce the said face. 25

We claim as our invention and production—

The design for a concave-section for separators, substantially as shown and described.

JOHN N. KAILOR.
MARSHAL T. REEVES.
